Inventor:

George J. Kling,

by: *W. Shadley*,
Attorney.

UNITED STATES PATENT OFFICE.

GEORGE J. KLING, OF ST. PAUL, MINNESOTA.

BREAD-BOARD.

1,313,900.

Specification of Letters Patent. Patented Aug. 26, 1919.

Application filed April 29, 1918. Serial No. 231,516.

To all whom it may concern:

Be it known that I, GEORGE J. KLING, a citizen of the United States, residing at St. Paul, in the county of Ramsey and State 5 of Minnesota, have invented a new and useful Improvement in Bread-Boards, of which the following is a specification.

This invention relates to improvements in bread boards, and has for its primary object the saving of crumbs of bread, cake 10 and other food, and of slices not immediately consumed.

A further object is to provide a structure in which the body of the structure is detachably held under spring action in a metal gutter so that the two elements may be 15 readily separated for cleaning and when assembled tightly locked together.

To these ends my invention comprises the 20 features of construction and combination of parts hereinafter particularly described and claimed.

In the accompanying drawing forming part of this specification, Figure 1 is a plan 25 of my invention; Fig. 2 is an edge view, part of the structure being broken away and in section, and Fig. 3 is an edge view of a detail of the body member.

My invention consists of a bread board 30 or palette A preferably although not necessarily in the form of a disk having in its periphery an annular groove 2. Arranged around the periphery of said palette is a marginal stand in the form of a gutter 3 35 in which the crumbs of bread or other food resulting from cutting on the palette are caught and retained. The gutter element is preferably made out of thin sheet spring metal spun or stamped. Its outer edge 4 is 40 folded over to form a smooth round surface and its inner upper edge is curved inwardly to produce an annular spring member which is adapted to engage the palette closely in the groove 2. The inner edge is 45 bent downwardly to form a depending support 6, said support being turned inwardly abruptly to produce a narrow annular shelf on which the lower edge of the palette is supported when the lock member 5 engages 50 the palette in the groove 2. The member 5 is sufficiently resilient, so that it will spring

into and out of engagement with the palette A in the groove 2 and coöperating with the shelf 7 supports the palette a short distance above the object on which the entire device 55 rests. Thus the gutter member performs the function of a stand to support the palette above the plane in which the lower extremity of the gutter member lies, making the device 60 more effective in use. The entire device is neat in appearance and sanitary due to the separability of the palette and gutter members. The device is also efficient, the locking feature holding the palette tightly embraced on the gutter member while the 65 latter supports it in elevated position. The palette member is preferably made out of wood or other material suitable for a cutting board. The construction is also simple and inexpensive and serves to prevent waste 70 by saving crumbs.

In accordance with the patent statutes, I have described the principles of operation of my invention, together with the apparatus which I now consider to represent the 75 best embodiment thereof, but I desire to have it understood that the construction shown is only illustrative, and that the invention can be carried out by other means and applied to uses other than those above set forth 80 within the scope of the following claim.

Having described my invention, what I claim as new and desire to protect by Letters Patent is:—

A bread board, consisting of a cutting 85 palette, having an annular groove in its periphery, and a thin circular shell formed into an annular gutter having its inner upturned edge extended inwardly to form a spring releasable engagement around the periphery of said palette in said groove with the gutter in position to catch crumbs from the palette, and a portion of said shell adjacent to said upturned edge being turned downwardly and inwardly to form an inwardly projecting annular shell above the plane of the lower portion of the gutter upon which the palette is adapted to be detachably supported. 95

In testimony whereof, I have signed my 100 name to this specification.

GEORGE J. KLING.
